JACK STAND

Jack W. Woldert, Jr., P.O. Box 4050,
Tyler, Tex. 75701

Filed Nov. 28, 1972, Ser. No. 310,006

Term of patent 14 years

Int. Cl. D12—05

U.S. Cl. D12—55

Fig. 1

Fig. 4

Fig. 2

Fig. 3

FIG. 1 is a perspective view from above and to the side of the jack stand of the invention;

FIG. 2 is a top plan view of the same;

FIG. 3 is a horizontal cross sectional view taken on the line 3—3 of FIG. 4; and

FIG. 4 is a side elevation of the jack stand, the opposite side being identical.

I claim:

The ornamental design for a jack stand, substantially as shown and described.
